FINGER RING

Bernard I. Mechanic, 2425 Oakton St.,
Evanston, Ill. 60202

Filed Feb. 5, 1973, Ser. No. 329,583

Term of patent 3½ years

Int. Cl. D11—01

U.S. Cl. D45—10 C

FIG. 1

FIG. 2

FIG. 3

FIG. 1 is a top plan view of a finger ring showing my new design;

FIG. 2 is a right side elevational view thereof—left side view is identical; and

FIG. 3 is a front elevational view thereof—rear elevational view is identical.

I claim:

The ornamental design for a finger ring, as shown and described.
